Alfred G. Jackson, Inventor
by David B. Moore, Attorney

UNITED STATES PATENT OFFICE.

ALFRED GEORGE JACKSON, OF BRISBANE, QUEENSLAND.

BICYCLE LUGGAGE-CARRIER.

SPECIFICATION forming part of Letters Patent No. 691,864, dated January 28, 1902.

Application filed April 22, 1901. Serial No. 56,841. (No model.)

To all whom it may concern:

Be it known that I, ALFRED GEORGE JACKSON, a subject of the King of Great Britain and Ireland, and a resident of George street, 5 Brisbane, in the State of Queensland, Australia, have invented a certain new and useful Bicycle Luggage-Carrier, of which the following is a specification.

My invention relates to an improved clip 10 for attaching to bicycles for carrying rifles, sporting-guns, or other articles; and it consists in a spring-band open at one end. The open end is provided with a link and eccentric chock, and on either end is a clip for securing 15 same to bicycle.

To fully describe the invention I will now refer to the drawings, in which—

Figure 1 is a perspective view of the attachment closed. Fig. 2 is a broken side view of 20 same open. Fig. 3 is a broken side view of same closed. Fig. 4 is a detail of heel-clip.

A is a metal band with a spring tendency, around the open end of which fits a link B, of 25 rectangular form, the band being slotted out on both sides to receive same. Onto this link is pivoted an eccentric chock C, having a pin 30 C' for manipulating same. Onto the open end of the band A is pivoted a clip D, thus providing for reversing the band and allowing the chock to be operated from either side of the bicycle.

E is a clip riveted or otherwise fixed to the heel of the metal band, or it may form an 35 integral part of same by strips being stamped out of each side of the metal band, turned over, and shaped to form a clip. (See Fig. 4.) Both clips are provided with thumb-screws for tightening same onto the frame of the bicycle.

40 In using my invention I attach it to the bicycle by fixing the clip D to the seat-pillar bar and the clip E to the bottom bar of the

frame of the machine. The butt-end of the rifle is inserted in the metal band A. On lifting the pin C' the eccentric chock, rotating 45 on the link B, presses the jaws of the metal band A together, which immediately grip the butt of the rifle. The muzzle end may either rest upon the handle-bars or be supported by a suitable clip secured to the head of the machine. The rifle can be instantly released by reversing the eccentric chock.

The construction of the metal band A may be modified by forming the same of two separate parts hinged together at the heel. 55

The invention is herein referred to as applied to rifles; but it will be obvious that it can be used for a variety of articles by modifying the shape of the metal band.

Having now described my invention, what 60 I claim as new, and desire to secure by Letters Patent, is—

1. A device of this character comprising an attaching-clamp, a spring-band having one end pivotally connected to the clamp and the 65 other end opposite the connection but free, a link surrounding the free and pivoted ends of the band, and means carried by the link for forcing the free end into close proximity to the pivoted end substantially as described. 70

2. A device of this character consisting of an attaching-clamp, a spring-band having one end pivotally connected to said clamp, and the other end opposite the connection but free, a link loosely surrounding the free and 75 pivoted ends of the band, and an eccentric chock carried by the link to force the free end of the band toward the pivoted end.

In witness whereof I have hereunto set my hand in presence of two witnesses.

ALFRED GEORGE JACKSON.
